US00D786612S

(12) United States Design Patent (10) Patent No.: US D786,612 S
(45) Date of Patent: * May 16, 2017

(54) COOKING VESSEL

(71) Applicant: Funtastic Limited, Chadstone, Victoria (AU)

(72) Inventors: Jose Antonio Esteban Bautista, Chadstone (AU); Luis Llorens Chanza, Chadstone (AU); Man Piu Billy Yip, Chadstone (AU)

(73) Assignee: Funtastic Limited, Chadstone (AU)

() Term: 15 Years

(21) Appl. No.: 29/545,157

(22) Filed: Nov. 10, 2015

(51) LOC (10) Cl. 07-02

(52) U.S. Cl.

USPC D7/359; D7/323; D7/354
